Matija Beshenich
INVENTOR

BY *Victor J. Evans*

ATTORNEY

WITNESS: *J. T. Wright*

UNITED STATES PATENT OFFICE.

MATIJA BESHENICH, OF MOLLENOUR, PENNSYLVANIA.

CHECK LOCK FOR MINE CARS.

Application filed March 14, 1928. Serial No. 261,570.

This invention relates to means for fastening a miner's tag or check to a car, the general object of the invention being to provide simple means for so fastening the tag or check to the car that it will be impossible for any one to remove the check and replace it by another one, thus preventing a dishonest miner from substituting his check for the check of the miner who has filled the car.

10 This invention also consists in certain other features of construction and in the combination and arrangement of the several parts, to be hereinafter fully described, illustrated in the accompanying drawings and specifically 15 pointed out in the appended claim.

In describing my invention in detail, reference will be had to the accompanying drawings wherein like characters denote like or corresponding parts throughout the several 20 views, and in which:—

Figure 1 is a view of portion of a car, showing the invention in use.

Figure 2 is a section on line 2—2 of Figure 1.

25 Figure 3 is an enlarged side elevation, showing a portion of the car with the invention in use.

Figure 4 is a section on line 4—4 of Figure 3.

30 Figure 5 is a view showing a portion of the inner side of a car, with the invention in use.

Figure 6 is a view of a tool used for removing the check from the car.

In carrying out my invention, I form an 35 opening 1 in one side of the car A to receive a wire 2, this wire being looped through the aperture in the check or tag B and then passed through the opening and twisted about a wedge-shaped strip 3 which is loosely connected with the inner side of the car by a 40 staple 4 passing through a hole 5 in the large

end of the strip. The hole in the car is made quite a distance from the top edge thereof so that after the check or tag has been fastened to the strip 3 by the wire and the car filled, 45 the strip, with the wire looped around the same, is covered by the coal in the car and thus it will be impossible for any one to remove the check and substitute another check for it. This will prevent a dishonest miner 50 from substituting his own check for the check of the miner who has filled the car.

The check is firmly held in place and there is no danger of it becoming detached from the car. After the car arrives at the dumping 55 point, the timekeeper or other person checking up the cars would run a tool, such as that shown at 6 in Figure 6, through the outer loop portion of the wire to break the wire at this point so that he can remove the check from 60 the car.

It is thought from the foregoing description that the advantages and novel features of my invention will be readily apparent.

It is to be understood that I may make 65 changes in the construction and in the combination and arrangement of the several parts, provided that such changes fall within the scope of the appended claim.

What I claim is:—

70 In combination with a mine car having a hole in one side thereof located below the top level of the coal in the car, a flexible member looped through the hole in a miner's check and passing through the hole in the car, a wedge-shaped strip pivotally connected with the inner wall of the car adjacent the hole therein and around which the flexible member is 75 twisted.

In testimony whereof I affix my signature.

MATIJA BESHENICH.
